UNITED STATES PATENT OFFICE

PERLEY R. WESLEY, OF PROVIDENCE, RHODE ISLAND, ASSIGNOR TO DAVOL RUBBER
CO., OF PROVIDENCE, RHODE ISLAND

DESIGN FOR A CRUTCH TIP

Application filed March 8, 1930. Serial No. 34,783. Term of patent 7 years.

To all whom it may concern:

Be it known that I, PERLEY R. WESLEY, a citizen of the United States, residing at Providence, in the county of Providence and State of Rhode Island, have invented a new, original, and ornamental Design for a Crutch Tip, of which the following is a specification, reference being had to the accompanying drawings, forming part thereof.

I claim:

The ornamental design for a crutch tip, as shown.

In testimony whereof I have hereunto signed my name.

PERLEY R. WESLEY.
